CLAIM

The ornamental design for a siren speaker, as shown and described.

DESCRIPTION

FIG. 1 is a top front perspective view of a siren speaker, showing my new design;

FIG. 2 is a front elevation view thereof;

FIG. 3 is a rear elevation view thereof;

FIG. 4 is a right elevation view thereof, the left elevation view being a mirror image thereof;

FIG. 5 is a top plan view thereof; and,

FIG. 6 is a bottom plan view thereof.

The broken lines shown in the drawings depict portions of the siren speaker that form no part of the claimed design.
